[57] CLAIM

The ornamental design for a beach blanket, and shown and described.

DESCRIPTION

FIG. 1 is a front elevational view of a beach blanket showing my new design;
FIG. 2 is a rear elevational view thereof;
FIG. 3 is a top end elevational view thereof;
FIG. 4 is a bottom end elevational view thereof; and,
FIG. 5 is a side elevational view thereof, the opposite design being a mirror image of that shown.

FIG.1

FIG. 2

FIG. 3

FIG. 4

FIG. 5
